UNITED STATES PATENT OFFICE.

ALDO CURIONI, OF NEW YORK, N. Y., ASSIGNOR TO MAURICE LEVY, OF NEW ROCHELLE, NEW YORK.

MACHINE FOR FEEDING, CUTTING, AND SEWING FABRICS.

Application filed February 25, 1922. Serial No. 539,191.

To all whom it may concern:

Be it known that I, ALDO CURIONI, a subject of the King of Italy, residing at 255 Edgecombe Avenue, New York, in the county of New York and State of New York, have invented certain new and useful Improvements in Machines for Feeding, Cutting, and Sewing Fabrics, of which the following is a specification.

10 My invention relates to a new and improved machine for making and sewing powder puffs. One of the objects of my invention is to provide a machine which shall automatically cut and partially sew together, two discs of fabric in proper relationship, so that the said discs thus sewed together can then be turned inside out and then have the sewing completed.

Another object of my invention is to provide a mechanism whereby a piece of ribbon will be automatically inserted, cut and sewed into position.

Another object of my invention is to provide a mechanism in which a cam shaft, having a series of cams thereon will control the action of most of the mechanism while the power for punching out or cutting out the pieces of fabric, will be derived from the relatively rapidly moving power shaft.

30 Another object of my invention is to provide a clutch or connection between the punches and the power shaft, which clutch or connection is controlled by the cam shaft.

Another object of my invention is to automatically disconnect the connection between the punch and the driving means therefor, so that the said punch will be operated only once to cut out a piece of fabric.

Another object of my invention is to provide a mechanism involving a sewing machine, the stitch of which is automatically altered during the sewing of the powder puff.

Another object of my invention is to provide an improved mechanism for automatically starting and stopping a sewing device to partially sew the puff.

Other objects of my invention will be set forth in the following description and drawings, which illustrate a preferred embodiment thereof.

Fig. 1 is a front elevation.

Fig. 2 is a side view looking at the right of Fig. 1.

Fig. 3 is a plan view.

Fig. 4 is a section on the line 4—4 of Fig. 2 and illustrates two pawls.

Fig. 5 is a section on the line 5—5 of Fig. 1.

Fig. 6 is a section on the line 6—6 of Fig. 5.

Fig. 7 is a top view of Fig. 6.

Fig. 8 is a view similar to Fig. 5 but showing the device with the knives or punches in the cutting position.

Fig. 9 is a view similar to Fig. 8, but showing the device after the cut has been completed.

Fig. 10 is a partial side view of Fig. 1 looking at the right thereof and showing the starting and stopping mechanism.

Fig. 11 is a plan view of Fig. 10.

Fig. 12 is a section along the line 12—12 of Fig. 10.

Fig. 13 is a section along the line 13—13 of Fig. 11.

Fig. 14 is a view similar to Fig. 13 but with the clutch in normal position.

Fig. 15 is a plan view of the feeding mechanism.

Fig. 16 is a side view of Fig. 15.

Fig. 17 is a section along the line 17—17 of Fig. 15.

Fig. 18 is a section along the line 18—18 of Fig. 15.

Fig. 19 is an end view of the sewing machine.

Fig. 20 is a section along the line 20—20 of Fig. 2.

Fig. 21 shows a view of the powder puff before it has been turned.

Fig. 22 is a perspective view of the completed powder puff.

The power for driving the various parts of the machine is derived from a pulley 1, which can be connected by a belt to any suitable source of power and also acts as a fly-wheel. The pulley 1 is rigidly mounted upon the shaft 2. The shaft 2 has an interior pulley 3 integral therewith, as can be seen in Figs. 11—14, and the fly-wheel 1 is locked to the shaft 2 and to the interior pulley 3 by means of the nut N, and shaft 2 has an enlargement adjacent nut N as can

be seen in Fig. 12. The pulley 1 is revolved continuously together with the shaft 2, by the source of power to which it is connected. As shown in Fig. 1, the shaft 2 has a sleeve 5 suitably keyed thereto and held thereto by means of a nut 6, and this sleeve 5 has a worm 7, formed thereon, which cooperates with the worm-wheel 8. As can be clearly seen in Fig. 2, the worm-wheel 8 is mounted upon a shaft 9 and the shaft 9 is mounted in a fixed sleeve 10 which forms a bearing. The shaft 9 is provided with a worm 11 and this actuates the cam shaft C by means of the worm-wheel 12. The cam shaft C drives nearly all the various parts of the mechanism, but the sewing machine is directly driven by the sleeve 5 by means of the sprocket wheels 14 and 15 connected by means of the chain 16, as shown in Fig. 2.

The two halves of the powder puff are automatically cut from two strips of cloth or other material and are fed into the mechanism in a superposed relation. The feeding mechanism is shown in detail in Figs. 15 to 18. A length of ribbon 19 is preferably fed into the mechanism together with the said two strips of cloth, and located between them. The two strips of cloth 17 and 18, together with the intermediate strip of ribbon 19, are fed to the cutting mechanism by a reciprocating carriage having a nipping device connected thereto. The carriage 20 is guided in its to and fro movement upon a frame 21. The carriage 20 is connected to the link 22 which is pivotally secured to the lever 23 which is oscillated. The lever 23 is oscillated in the plane shown in Fig. 1, being integral with a sleeve 24' fastened to the shaft 25'. The shaft 25' is connected to the rod 26'. The rod 26' is connected to a lever 27 operated by a cam 28 on the cam shaft and shown in Fig. 3. The general arrangement whereby the said cam 28 operates the said parts is similar to that shown in Fig. 5 in connection with other parts to be later described.

By the action of the parts before mentioned, the carriage 20 is reciprocated. The link 22 is not rigidly secured to the carriage 20, but it has a certain relative movement with respect thereto. This is accomplished by having the pin 22' of the link 22 movable in a slot 24 of the frame of the carriage 20 so that the pin 22' can move for a predetermined distance before it reaches the end of the slot 24, when it actuates the carriage 20. The object of this is to release a clamp which holds the cloth against movement before the said cloth is seized by the nipper of the carriage and fed forwardly. The pin 22' is connected to bar 31 which is moved independently of carriage 20 and has projections 32 and 42'. The cloth clamp consists of a lever 25 pivot-

ed at 26 and normally urged to revolve in a clockwise direction by the tension spring 27', shown in Fig. 16. The revolution of the clamping lever 25 can be prevented by means of the pawl 28', which is pivotally secured to the end of the lever 25 at 29. As shown in Fig. 15, the clamp shaft 26 carries two toothed levers 30, one of which is shown in Fig. 17. As shown in Fig. 16, as soon as the link 22 is operated the projection 32 of bar 31 pushes the pivoted pawl 28' to raise it and keep it temporarily raised so as to release the toothed levers 30 from the cloth and permit the cloth to be fed forwardly.

As soon as the clamping levers 30 have been raised and while they are temporarily held in a raised position, the cloth is nipped and fed forwardly. The nipper 33 is pivotally secured at 33' to the end of the lever 34, which is mounted upon the shaft 34'. The nipper 33 is urged downwardly by a blade spring B secured to lever 34, so that it tends to assume the position shown in Fig. 17. This shaft 34' has cups 35 secured thereto and these are upwardly urged by compression springs 36 secured to the carriage 20. These tend to normally cause the nippers 33 to engage with the cloth, but a control lever 37, having a roller or pin 40 and roller 42 and mounted upon the shaft 34', is normally held upwardly by means of a plate 38, held adjustably by means of the set screws 39. The plate 38 is secured to the frame 21 so that it remains stationary at all times.

When the carriage 20 has been moved sufficiently to the left so that the pin 40 of the control lever 37 clears the adjustable plate 38, the levers 30 having first been raised, then the nipper 33 engages the cloth and feeds it forwardly. This is shown in dotted lines in Fig. 17. The adjustment of the plate 38 renders it possible to regulate the amount of cloth which is fed forwardly and since the cloth at the left of the punch is positively clamped by the member 30 there is no dragging when the punch performs its action or when the carriage moves backward. As soon as the pawl 28' passes behind the end of the projection 32, it drops into the space or slot 41 between projections 32 and 42' of bar 31, so as to allow members 30 to clamp the cloth. As seen in Fig. 16, pawl 28' can be freely revolved counterclockwise for about 90°, as shown in dotted lines.

Upon the return movement of the lever 23, the carriage first remains stationary until the pin 22' has reached the right-hand side of the slot 24. The first movement of the projection 42' of bar 31, which has an inclined right-hand end, is to act upon the roller 42 of the lever 37 so as to release the nipper while the pawl 28 is rocked into

the horizontal position by the right-hand movement of projection 32, without, however, raising the cloth clamp 30.

Hence, before the carriage is moved to the right to start a new feeding stroke, its nipper is positively released from the cloth, while the cloth is still held by the clamp, so as to prevent any backward movement thereof.

10 The machine is now ready for the punching operation, whereby two discs of the fabric, together with an intermediate strip of ribbon are cut to be fed to the sewing machine. The punching or cutting mechanism is shown in Figs. 5, 8 and 9.

Before the cloth is cut, the outside clamping shell 43 is caused to descend under the action of the spring 55 in space 44, so as to clamp the fabric and ribbon and hold them while the punching or cutting operation is performed, as is clearly indicated in Fig. 8. The upper cutting die 45 is then caused to descend and cooperate with the lower cutting die 46 so as to cut out the discs of fabric. The parts are guided in the guides 47. The lower guide 47 is provided with a bolt 48, which enters a corresponding groove of the shell 43, so as to prevent it from turning. The lower cutting die 46 is clamped to the holder 49 by means of the bolt 49', and locking member 51, whereby it is held to the frame F. The frame F and the guides 47 and the holder 49 are preferably integral.

15 The holding and punching mechanisms are operated by means of an eccentric 50 mounted upon the sleeve 4 and located within the eccentric rod 51, which is caused to move up and down when the sleeve 4 revolves in the direction of the arrow shown in Fig. 5. The rod 51 is carried in a bearing suitably mounted on the main frame or casing F. The rod 51 is internally threaded at the bottom thereof and it carries an internal pitman 52, which is pivotally secured at 53 to the upper cutting die 45. As clearly shown in Fig. 5 and Fig. 8, the upper cutting die 45 is surrounded by the outer shell or clamping sleeve 43, and the shell 43 and upper die 45 are connected so as to have a relative movement by means of the head H of said die 45 and the spring 55. Hence, when the upper cutting die 45 is directly depressed, the spring 55 is compressed so as to cause the downward movement of the upper clamp 43. The upper clamp 43 first engages the strips of fabric 17 and 18 and then when the upper cutting die 45 is further depressed, as shown in Fig. 8 two circular discs of fabric, and an intermediate strip of ribbon, 19, are cut out and placed upon the top of the plunger 56. The sleeve 58 located within the upper cutting die 45 and which is moved downwardly, thereby, may be called the plunger sleeve. This sleeve 58 is slotted

at 60, and a lever 59 fits into this slot. The lever 59 is pivotally mounted on shaft 61 and it is connected to tension spring 61' which tends to hold it in the position shown in Fig. 5.

When the upper die 45 descends it forces the sleeve 58 downwardly by means of the cooperating shoulders. This revolves the lever 59 downwardly and in order to temporarily keep the sleeve 58 in its intermediate position, so that it can be forced still lower by the cam 62, a bell crank lever 63 is provided, which is pivotally mounted at 64, and is urged into the position in which it locks lever 59 by tension spring 71, adjusted by the threaded member 72. Lever 63 has an upper arm 67', which can be actuated by the pin 66 of the cam shaft C, shown in Fig. 8, so as to move lever 63 to unlocking position. Hence, while the sleeve 58 is held in its intermediate position by the locking lever 63, the cam groove of cam member 62 operates to further depress the lever 67 which is pivotally mounted at 64 and is connected to the lever 59 by means of the adjustable link 68, so that the said sleeve 58 is forced to the position shown in Fig. 9 from the intermediate position shown in Fig. 8, whereby the plunger 56 is depressed against the action of the compression spring 69 and the severed fabric is forced upon and held by needles or pins 70.

In order to keep the plunger 56 in its lower and depressed position, it is mounted upon a revoluble rod 74, shown in Fig. 5, having a piston-like head 73, provided with a slot in its wall, through which the bottom of a pawl 77 pivoted to said head 73 may project. The rod 74 has a vertical recess or hollow in the bottom thereof. In this recess is mounted the compression spring 75 shown in Fig. 6, which downwardly actuates the slideable rod 76, which acts upon the horizontal member of said pivoted pawl 77. This horizontal member of pawl 77 is adapted to fit in a slot of said rod 76. When the plunger 56 is depressed, the rod 74 and head 73 are also depressed while the rod 76 is urged downwardly by the spring 75. Since

the head 73 slides with some friction, the spring 75 becomes compressed and rod 76 tends to revolve pawl 77. Hence when the bottom of said pawl 77 passes below the bottom of the revoluble spindle 78, the bottom of said spindle 78 is engaged by the bottom of the pawl 77, which prevents the said rod 76 from moving upwardly until the said pawl 77 is tripped since the movement of the pawl 77 is retarded by sufficient friction to prevent the plunger 56 from returning to its upper position. The plunger 56 is thus held in its lower position until the carriage 79 has been revolved about 240° and after the sewing has been completed.

In order to have the bunch and the ac- 130

companying mechanism properly operated, this is operated by the power shaft 2, which is always revolved at a relatively higher speed, but these parts are connected to the main shaft by a clutch mechanism, which is controlled by the cam shaft C, which is revolved at relatively lower speed.

The cam shaft C has a cam 80, shown in Fig. 10, and this is adapted to alternately prevent or permit the revolution of the bell crank lever 81 pivoted at 82 and adapted to be actuated by the tension spring 83. In the position shown in Fig. 10, the revolution of the bell crank lever 81 is just beginning. These parts are shown on a larger scale in Fig. 13 in which the cam 80 has been revolved further. When the bell crank lever 81 is turned, it moves a link 83' to the right. The link 83' is shown in Fig. 13 at the end of its movement. As shown in Fig. 10 the link 83' is connected by means of a pivotal connection to extension member 84 connected to the bottom of rod 86, which passes through the sleeve 87, having a toothed head at its bottom as shown in Fig. 14. The extension 84 may be connected to the said toothed head so as to revolve it in only one direction by means of the tooth 85 shown in Fig. 14, so that when the extension 84 is revolved clock-wise in Fig. 11, the rod 86 is also revolved clock-wise and the sleeve 87 may also be revolved clockwise if its head is in mesh with member 84 as shown in Fig. 13. The tooth 85 must then engage the corresponding shoulder. The lower position of the rod 86 and of the member 84 are shown in Fig. 14, when the toothed member 84 is out of mesh with sleeve 87. The sleeve 87 is provided with a projection 92 which tends to limit the counter-clock-wise movement thereof which is produced by the compression spring 91 shown in Fig. 12. The abutment 90 which is adjustably held in bearing member 88 as shown in Figs. 13 and 14 limits the movement of member 92, so that it will not contact with pulley 3. Hence the revolution of the toothed member 85 can revolve the sleeve 87 against the force of the compression spring 91. When the sleeve 87 is revolved in the clock-wise direction as shown in Fig. 12, the extension 92 thereof is moved from the full line position to the dotted line position shown in Fig. 12, thereby releasing the pawl 93 which is pivotally mounted at 95, as shown in Fig. 13, so that it is then free to engage the corresponding shoulder 96 of the internal pulley 3 of power shaft 2 as shown in Fig. 13. The pawl 93 is actuated by a compression spring 98. When the pawl 93 is in locked position as shown in Fig. 13, then the outer sleeve 4 to which it is pivoted and which has the eccentric 50, is turned and the cutting or punching mechanism is operated, as shown

in Fig. 8. Before a revolution of the sleeve 4 has been completed, it is highly desirable to trip or release the pawl 93, so that the cutting mechanism cannot be operated for more than one stroke. This is accomplished by means of the cam C' mounted upon the sleeve or outer shaft 4 as shown in Fig. 11, which operates by means of a bell crank lever 100, pivotally mounted at 101 to depress the rod 86 against the action of the compression spring 102. When the rod is depressed, then as shown in Fig. 14, the member 84 is depressed so that its tooth no longer engages with the sleeve 87 and the sleeve 87 is then snapped into the position shown in full lines in Fig. 12 by the spring 91, so that the extension 92 will then engage with pawl 93 and force it out of engagement with the pulley 3, connected to the shaft 2.

The carriage 79 is intermittently revolved by means of the cam 104 which operates to depress the pivoted lever 105 and the link 106 which revolves the segment 110 mounted on shaft 109 by means of the extension 108. This segment 110 has bevel teeth 107 which cooperate with corresponding bevel teeth 111 on a collar 112 and this collar 112 is adapted to engage a pawl 114 of the carriage 79. The pawl 114 is urged upwardly by a compression spring 115 as shown in Fig. 4. Hence when the collar 112 is revolved in one direction it engages the pawl 114 and revolves the carriage 79 for an arc of 180° and when the carriage 79 is revolved backwards, it depresses the pawl 114 so as to have no effect upon the carriage.

An ordinary V-shaped pawl 120 connected to frame F and which is urged upwardly by a compression spring 121, fits into a recess of the carriage and ensures that it shall be positively held in the desired position.

When the carriage has thus been revolved 180°, the two superposed discs of fabric which have been forced on needles 70, and the intermediate ribbon are then presented to the action of the sewing machine which may be of any approved type.

The sewing mechanism is actuated by a belt B, carried on a pulley 115' mounted upon a shaft 116 which is actuated by a bevel gear 117, driven by the shaft of the sprocket 15. The belt B is not made too tight, so that it can slip whenever the sewing machine must have the mechanism thereof stopped.

The action of the sewing machine is controlled by means of the lever 125 pivoted at 126. The lever 125 is connected by means of a link 127 to a control lever 128 which is actuated by a pin fitting in the cam slot 130 in a cam mounted upon cam shaft C. The lever 128 is pivoted at 124.

In order to start the sewing machine into operation the lever 125 is moved into the 130

uppermost position shown in Fig. 2 in dotted lines, so that the pressure foot F' is raised sufficiently to permit the cloth to pass underneath it. At the same time the stop S is raised so as to permit the revolution of the pulley 131 mounted upon the same shaft as the drive pulley 132. The stop S is pivoted at 133 and it is connected by means of the lever 134 to the bell crank lever 125.

19 After the pressure foot has been raised sufficiently to allow the fabric to pass underneath it, the said lever 125 is now moved to the lowest of the three positions d shown in dotted lines in Fig. 2, in which the fabric is sewed with a comparatively long stitch as shown by d' in Fig. 21. The regulation of the stitch has heretofore been well-known in sewing machines, and it is accomplished by varying the movement of the feed dogs there-

20 of, and it is desired to automatically vary the length of the stitch, so that it shall be quite close and strong at the completion of the sewing operation, so as to firmly secure the ends of the stitched portion. The feed dog D is pivoted at 136 and it is actuated by the link 137, which is slotted and which is connected to an eccentric 138 mounted upon the shaft 139 and forming part of the sewing machine, so that by revolving the eccentric the link 137 can be moved to and fro. The dog D has a segmental slot 138' and the length of the feed stroke thereof varies according to whether the pin 139' of link 137 is moved up or down in the said segmental slot 138'. This is accomplished by means of the control member 140 pivoted at 141 and pivotally connected at 142 to the link 143. The control member 140 is actuated by the tension spring 145, which can be adjusted by means of the bolt 146. The rod 144 connected to link 143 carries an adjustable collar 148, which limits the movement thereof by contracting with a cross bar of frame F'. The rod 144 is connected to lever 125 and the cam slot 130 is of such contour that the stitch is automatically shortened near the beginning and end thereof, as shown in Fig. 21.

22 After the sewing has been completed, the carriage 79 is again revolved, when the bottom of pawl 77 strikes any suitable cam projection T in the position shown in dotted lines in Fig. 2 so that it is tripped and member 56 is free to rise and remove the partially sewed article from pins 70 and force it on pins 70' connected to plate P. The plunger 56 then slides along the underside of plate P until it reaches the lower die when it is moved into the position shown in Fig. 8.

23 The operator causes two strips of fabric together with an intermediate strip of ribbon to be fed to the feeding mechanism, shown in Figs. 15-18. The pieces of fabric and the ribbon are led between the punching

devices and firmly held there. Then the cam shaft throws in the clutch which connects the punching mechanism and the power shaft, so that the two pieces of fabric, together with an intermediate strip of ribbon, 70 are forced upon the disc and the disc is depressed so that the pieces of fabric and the ribbon are locked upon pins 70 and the said disc 56 is held in its lowest position. The punching mechanism can be operated 75 only once to cut out any two pieces of fabric.

24 Then the carriage is revolved so as to present the discs of fabric and the ribbon to the sewing mechanism while they are accurately held in place by the needle 70. The sewing mechanism is now set into operation and it automatically partially sews the puff, with a regulated stitch as before explained. When the sewing is completed, the sewing machine is stopped and the carriage is revolved so as to present new discs of fabric to the sewing mechanism, and to cause the pawl locking the plunger to be tripped so that the plunger flies upward, releasing the fabric from the needles and forcing it on the upper needles. The partially sewed puff is now turned inside out and the sewing is completed so as to produce the article shown in Fig. 22.

25 I have shown a preferred embodiment of my invention, but it is clear that numerous changes and omissions can be made without departing from its spirit.

26 This machine is an improvement on that shown in my former application Ser. No. 463,018.

27 It is obvious that the constructions hereinbefore described can be applied to other purposes than the manufacture of powder puffs.

28 It is to be understood that where I refer in the claims to any of the parts hereinbefore mentioned by means of the number used to designate such part or parts in the drawings herein, that I do not desire to be limited to the precise construction or operation of such part as shown in the preferred embodiment before described.

29 I claim:

1. In combination, a support upon which superposed strips of fabric may be laid, punching mechanism adapted to punch out pieces from said strips of fabric, means for operating said punching mechanism, feeding means located in front of said punching mechanism and adapted to feed the strips of fabric thereto, clamping means located behind the said punching means and adapted to hold said strips of fabric, and means for operating the said clamping means so as to clamp the said strips of fabric while the punching means are being operated and while the feeding mechanism is inoperative.
2. In combination, a support upon which superposed strips of fabric may be laid,

punching mechanism located adjacent the said support and adapted to punch out pieces of fabric from the said strips, clamping means 30, located behind the said punching mechanism, means for operating the said clamping means 30, so as to render them operative or inoperative for clamping the said strips of fabric, said operating means for the clamping means 30 being adapted 10 to force the clamping means 30 to operative position so as to clamp the cloth while the punching mechanism is being operated.

3. In combination, a support upon which superposed strips of fabric may be laid, 15 clamping means 30, means for actuating the same so as to render them operative or inoperative, a carriage 20 having nipping means secured thereto, means for actuating the said carriage to and fro but having a 20 relative movement with respect thereto, the said carriage operating means being adapted to first raise clamping means 30 before the nipping means operate to feed the fabric forwardly, and punching mechanism adapted 25 to punch out pieces from said strips of fabric.

4. In combination, a support upon which strips of fabric may be laid, punching mechanism adapted to punch out pieces of 30 fabric from the said strips, clamping means 30, means adapted to raise and lower the said clamping means 30, a pawl 28', a carriage 20 having a slot 24 and also having nipping means mounted thereon, a movable 35 bar 31 having projections 32 and 42' separated by a slot 41, a link 22 connected to said bar 31, said link 22 having a pin 22' slideable in said slot 24 of said carriage 20, and means adapted to reciprocate said link 40 22, the said parts being so dimensioned that when said bar 31 is first moved the projection 32 first acts upon the pawl 28' to release the clamping means 30 from the said strips of fabric, the carriage 20 being then operated 45 by said link 22 so that its nipping means engage the cloth and move it forwardly until the said pawl 28' drops into the slot 41, whereby the strips of fabric are gripped by the clamping means 30 upon the return 50 stroke of the carriage.

5. In combination, a support upon which strips of fabric may be laid, punching mechanism adapted to punch out pieces of fabric from the said strips, clamping means 30 55 having a pawl 28', a carriage 20 having a slot 24, a bar 31 having projections 32 and 42' separated by a slot 41, said bar 31 having a link 22 connected thereto, said link 22 having a pin 22' movable in said slot 24 60 of said carriage 20, a crank shaft, and means adapted to be operated by the revolution of said crank shaft and adapted to reciprocate said link 22.

6. In combination, a support upon which 65 strips of fabric may be laid, punching mech-

anism adapted to punch out pieces of fabric from said strips, clamping means 30 having a pawl 28', a frame 21', a carriage 20 having a slot 24 and adapted to be moved on said frame 21, nipping means mounted 70 upon said carriage 20 and including a lever 37 having a roller 42, a movable bar 31 having the spaced projections 32 and 42', a link 22 connected to said bar 31 and having a pin 22' movable in said slot 24 of said carriage 20, and supplemental means adapted 75 to adjustably regulate the engagement of the said nipping means with the said fabric.

7. In combination, a support upon which strips of fabric may be laid, punching mechanism adapted to punch out pieces of fabric from the said strips, clamping means 30 having a pawl 28', a frame 21, a carriage 20 having a slot 24 and also having nipping means mounted thereon which include 80 a lever 37 having a pin 40 and a roller 42, said carriage 20 being mounted on said frame 21, a movable bar 31 having the spaced projections 32 and 42', a link 22 connected to said bar 31 and having a pin movable in said slot 24 of said carriage 20, and a plate 38 adapted to co-operate with the pin 40 of the said lever 37, so as to control the release of said lever 37 to permit the nipping mechanism to engage the cloth. 85

8. In combination, a support upon which strips of fabric may be laid, punching mechanism adapted to punch out pieces of fabric from the said strips, clamping means having a pawl 28', a frame 21, a carriage 20 100 having a slot 24 and mounted on said frame 21, said carriage 20 having nipping means mounted thereon which include a lever 37 having a pin 40 and a roller 42, a bar 31 having spaced projections 32 and 42', a link 105 22 connected to said bar 31 and having a pin 22' movable in said slot 24 of said carriage 20, and a plate 38 adapted to co-operate with said pin 40 so as to control the release of said lever 37 to permit the nipping mechanism to engage the cloth, and means adapted to adjustably hold said plate 38 in 110 the line of movement of the carriage 20.

9. In combination, a support upon which strips of fabric may be laid, punching mechanism adapted to punch out pieces of fabric from the said strips, a shaft having a relatively high speed of revolution, clutch mechanism between the said punching mechanism and the said shaft and adapted to connect them together and a cam shaft having a relatively slower revolution than the first mentioned shaft, and adapted to control the operation of the said clutch so as to render the same operative and inoperative. 115

10. In combination, a support upon which strips of fabric may be laid, punching mechanism adapted to punch out pieces of fabric from the said strips, a shaft having a relatively high speed of revolution, clutch mech- 120 125

anism between the said punching mechanism and the said shaft and adapted to connect them together and a cam shaft having a relatively slower revolution than the first mentioned shaft, and adapted to control the operation of the said clutch so as to render the same operative and inoperative, and means for disengaging the said clutch when the said punching mechanism has performed a single stroke.

11. In combination, the inner shaft 2 having a pulley 3, an outer shaft 4 having an eccentric 50, a pawl 93 connected to an outer shaft 4 and having a spring 98, the 15 said pulley 3 having an internal shoulder 96 and means operated by a cam shaft for controlling the position of the pawl 93 so that it either engages, or is disengaged from the shoulder 96.

12. In combination, an inner shaft 2 having a pulley 3, an outer shaft 4 having a cam C', an eccentric 50, a pawl 93 having a spring 98 and pivotally secured to said shaft 4, the said pulley 3 having an internal shoulder 96 adapted to be engaged by the said pawl 93, a cam shaft, a sleeve 87 having a movable pawl control member 92 mounted thereon, and connecting means adapted to be operated by the revolution of 30 said cam and adapted to revolve the sleeve 87 in one direction, and means adapted to be actuated by cam C' to cause the said connecting means to be disconnected.

13. In combination, an internal shaft 2 having a pulley 3, an outer shaft 4 having an eccentric 50, a pawl 93 pivotally connected to the outer shaft 4 and having a spring 98, the said pulley 3 having an internal shoulder 96, a sleeve 87 mounted on 40 a shaft 86, a pawl control member 92 secured to the sleeve 87, said sleeve 87 having a tooth, said shaft 86 being adapted to be moved up and down in the sleeve 87 and having a toothed member 84 secured to the bottom thereof, said member 84 having a tooth 85 adapted to mesh with a tooth of the sleeve 87 located at the bottom of said sleeve, a cam shaft, means connected to said cam shaft and adapted to be operated by 45 the revolution of said cam shaft and to revolve the said toothed member 84 so as to cause the revolution of the sleeve 87 and move the member 92 to permit the pawl 93 to engage the shoulder 96 of the cam C', 50 and connecting means between the cam C' and the shaft 86 and adapted to depress the shaft 86 when the cam is actuated, so as to unmesh tooth 85 from the said tooth on the sleeve 87.

14. In combination, a lower cutting die 46 and an upper punch 45, a clamping sleeve 43 and means adapted to operate the same so as to clamp a piece of fabric before the punch 45 is operated, a revoluble spindle 78

having needles 70 mounted thereon, an inner 65 sleeve 58 adapted to be moved down together with the punch 45, and means adapted to thereafter further depress the sleeve 58 so as to force the punched out fabric on the 70 needles 70.

15. In combination, a revoluble spindle 78 having needles 70, a slidale and revoluble rod 74 having a plunger 56 and means for forcing punched out pieces of fabric upon 75 said plunger 56 and for depressing it until the said pieces of fabric are engaged by the needles 70 and means for holding said plunger 56 in its depressed position.

16. In combination, a plunger 56 mounted upon a revoluble and slidale rod 74 80 having a spring 69, a revoluble spindle 78 having needles 70, an upper punch 45, a lower cutting die 46 adapted to co-operate with the punch 45 and having a clamping sleeve 43 and a depressing sleeve 58, a lever 85 59 adapted to co-operate with the sleeve 58 and having locking means adapted to prevent the upward movement of the depressing sleeve 58 when the punch 45 is moved upwardly, a cam shaft C, a plunger 56, and means adapted to be actuated by said cam shaft C and adapted to actuate the lever 59 so as to further depress the depressing sleeve 58 and force the fabric upon the plunger 56 and then move the plunger 56 downwardly until the fabric is engaged by the needles 70, and means adapted to lock the plunger 56 in this depressed position.

17. In combination, a revoluble hollow 100 spindle 78 having the needles 70, a revoluble and slidale rod 74, said rod 74 having a plunger 56 and a spring 69, a pawl 77 associated with said rod 74, said pawl 77 being adapted to engage the bottom of the 105 spindle 78 and to hold the plunger 56 in the lower position.

18. In combination, a revoluble hollow spindle 78 having needles 70, a revoluble 110 and slidale rod 74 carrying a plunger 56, a spring 69 adapted to force the rod 74 to its upper position, a head 73 associated with said rod 74, the said rod 74 having a spring 75 fitting in a recess thereof, the 115 said head 73 carrying a rod 76 adapted to co-operate with said spring 75, a pawl 77 pivoted to the head 73 and adapted to engage the bottom of the spindle 78, a portion of the said pawl 77 being connected to the said rod 76 so that when the spring 75 is compressed, the rod 76 will be adapted to be moved to revolve the pawl 77 so that it will engage the bottom of the 120 hollow spindle 78.

In testimony whereof I hereunto affix 125 my signature.

ALDO CURIONI.
